His Attorney.

UNITED STATES PATENT OFFICE

GEORGE P. ADAIR, OF SCHENECTADY, NEW YORK, ASSIGNOR TO GENERAL ELECTRIC COMPANY, A CORPORATION OF NEW YORK

SIGNALING SYSTEM

Application filed February 18, 1928. Serial No. 255,484.

My invention relates to signaling systems and more particularly to high frequency communication systems of the duplex type in which automatic means are provided for controlling the volume of the signal which is received from remote points and for protecting the receiving equipment against energy which reaches it from the associated transmitter.

10 Still more particularly my invention relates to systems of the type disclosed in application Serial No. 161,191 of Lester F. Bird, filed January 14, 1927 and which is assigned to the same assignee as the present application. In that application a device is disclosed comprising a three element electron discharge device, the anode-cathode circuit of which comprises a shunt to the receiving channel. The potential of the grid of this 20 device is controlled by a resistance which is connected in series with the discharge path of both the detector of the receiving circuit and the oscillation generator of the associated transmitter. In this way the impedance of the three element device may be controlled both in response to the signal intensity as indicated by the magnitude of the detector anode current and to the functioning of the 25 oscillation generator. Thus this shunt connected control device in the receiving circuit serves both to protect the receiver against energy which reaches it from the associated transmitter and also to control the volume of the received signal.

30 While the device disclosed by Mr. Bird in the above application has proved to be a very satisfactory one in commercial practice I have found that certain simplifications in the circuit may be made which result in improved 35 operation of the system as a whole and at the same time in reduced cost of construction and maintenance.

The novel features which I believe to be 40 characteristic of my invention will be set forth with particularity in the appended claims. My invention itself, however, both as to its organization and method of operation, together with further objects and advantages thereof may best be understood by 45 reference to the following description taken

in connection with the accompanying drawing, in which the single figure represents an embodiment of my invention.

Referring to the drawing 1 represents a portion of the transmitter circuit and 2 the essential elements of the associated receiving circuit to which I have applied my invention. In the receiving circuit I have shown an electron discharge device 3, which is employed as a detector. The input circuit to this detector is supplied with received signal currents through a channel which includes the conductors 4, which lead to any suitable antenna or wire line circuit, such as a power distribution system from which the signals are received, hybrid coil 5 and transformer 6. The secondary winding of this transformer is connected through condensers 7 and 8 the latter of which is connected in parallel with resistance 17 to the grid and cathode respectively of the electron discharge device 3. The output currents from this discharge device are supplied from the anode circuit thereof through the transformer 9, hybrid coil 10 and output circuit 11 to any suitable receiving instrument or signal circuit such as a telephone, or telephone line.

In the transmitting circuit are employed an electron discharge oscillation generator 12 to the grid and anode of which is connected the usual oscillatory circuit of which the capacitance is represented at 13. The high frequency currents generated by this device are transmitted through any suitable amplifying equipment 14 to the hybrid coil 5 from which they are communicated to the transmission media by the conductors 4. The discharge path of the oscillation generator 12 is included in a circuit leading from the anode thereof through the choke coil 15, source of potential 16, resistance 17, conductor 18, space between the cathode and anode of control electron discharge device 19, conductor 20 and the space between the cathode and anode of discharge device 12. Signal currents from any suitable signaling device or telephone instrument may be impressed upon the grid of the control device 19 through the circuit 11, hybrid coil 10 and amplifying means 21. These currents will also be caused

to modulate the currents which are produced by the oscillation generator 12 by any suitable means, not shown. One means whereby this modulation may be effected is illustrated in Patent No. 1,696,590, L. F. Bird, issued December 25, 1928. Condenser 28 is connected between the anode and cathode of device 19 to prevent modulation of the transmitter output currents by this device. En-

10 ergy is supplied for heating the cathodes of the discharge devices 12 and 19 through suitable cathode transformers 22 and 23.

In the receiving circuit an electron discharge device 24 of the two element type, or 15 of the three element type, in which the grid and anode are connected together to constitute a single electrode is connected in shunt with the receiving circuit and hence in shunt with the tuned circuit 25, which comprises 20 the input circuit of the detector 3. The anode circuit of the device 24 is suitably biased with respect to the cathode thereof by means of a source of potential 26, such that the device has no substantial effect upon signals 25 which are received having substantially normal intensity. This bias, however, is such that it is overcome by signals of greater than normal intensity, which thereby cause the impedance between the anode and cathode of 30 this device to be diminished. This diminution of the impedance causes the device 24 to become an effective bypass for a portion of the signal currents and a shunt upon the tuned circuit 25. The sharpness of the tuning of 35 circuit 25 is then lessened and this effect together with that of bypassing a portion of the signal currents serves to diminish the intensity of the signals which reach the grid of detector 3. The impedance of this shunt path 40 will of course be dependent upon the intensity of the received signal and will vary therewith. Thus to signals which are received having normal intensity, the device 24 is ineffective to produce any substantial diminution 45 thereof, but as soon as signals of greater than normal intensity are received the impedance of the device 24 becomes diminished, thereby causing a portion of these signals to be short circuited through the device 24, and 50 the tuned circuit to be affected. In this way a very effective volume control of the received signals may be had.

This device is also caused to respond to 55 operation of the transmitting circuit. It will be noticed that the resistance 17 is connected between the cathode and anode of the device 24 and is also connected in series with the discharge path of the oscillation generator 12. Thus whenever current flows in the discharge 60 path of the oscillation generator a potential will appear across the resistance 17 having the polarity indicated on the drawing and tending to drive the anode thereof strongly positive with respect to the cathode. In this 65 way the impedance of device 24 is greatly

diminished and this device then becomes a shunt circuit of low impedance to currents which reach the receiver and also causes the tuned circuit to be affected in the manner described. Thus the receiving circuit is rendered insensitive to excessive and disturbing potentials which may reach it from the transmitting circuit during operative periods thereof.

Current is caused to flow in the discharge 75 path of the oscillation generator by means of the control device 19 upon which the voice currents are impressed. This device normally has sufficient impedance between its cathode and anode to preclude the flow of anode current through the oscillation generator and hence to preclude the operation of the device 12. When the operator speaks into the microphone voice currents will be supplied through the audio amplifier 21 to the grid of device 80 85 90 95 100 105 110 115 120 125 130 135 140 145 150 155 160 165 parting from the spirit and scope of my invention as set forth in the appended claims.

What I claim as new and desire to secure by Letters Patent of the United States, is:

- 5 1. In a signaling system, a receiving circuit, a transmitting circuit, an electron discharge device having an anode and a cathode, the space between said anode and cathode being connected in shunt with said receiving circuit and the impedance thereof being variable in response to the intensity of the received signals, and means responsive to operation of said transmitting circuit for impressing a potential upon said anode with respect to said cathode thereby to diminish the impedance of said discharge device.
- 10 2. In a signaling system, a receiving circuit, a transmitting circuit, an electron discharge device having an anode and a cathode, the space between said anode and cathode being connected in shunt with said receiving circuit, means for biasing said anode with respect to said cathode such that said device has substantially no effect upon received signals of normal intensity but has diminishing impedance to signals of greater than normal intensity, a resistance connected between said anode and cathode and means responsive to operation of said transmitting circuit for causing a current to flow through said resistance to diminish the impedance of said discharge device thereby to effect the intensity of currents flowing through said receiving circuit.
- 15 3. In a signaling system, a receiving circuit and a transmitting circuit, said transmitting circuit including a normally inoperative electron discharge oscillation generator, an electron discharge device connected in shunt with said receiving circuit having an anode and cathode, means for biasing said anode with respect to said cathode such that said device has substantially no effect upon received signals of normal intensity but has diminishing impedance to currents of intensity greater than normal, and a resistance connected between said anode and cathode, said resistance being also connected in series with the discharge path of said oscillation generator whereby said receiving circuit is rendered insensitive during operative periods of said oscillation generator.
- 20 4. In a signaling system, a transmitter and a receiver, a tuned input circuit to said receiver, a two electrode electron discharge device having an anode and cathode connected in shunt with said tuned circuit, said device having impedance such that it has no substantial effect upon received signals of normal intensity but which diminishes in response to signals of intensity greater than normal, and means for producing a positive potential upon said anode with respect to said cathode responsively to operation of said transmitter to diminish the impedance of said device,

thereby to cause said device to constitute a low impedance shunt across said receiving circuit and to affect the tuning of said input circuit.

In witness whereof, I have hereunto set my hand this 17th day of February, 1928.

GEORGE P. ADAIR.
